UNITED STATES PATENT OFFICE.

WILLIAM A. SMITH, OF DENVER, COLORADO, ASSIGNOR TO THE DENVER ROCK DRILL MANUFACTURING COMPANY, OF DENVER, COLORADO, A CORPORATION OF DELAWARE.

ROCK-DRILL.

1,267,705.

Specification of Letters Patent. Patented May 28, 1918.

Application filed December 16, 1916. Serial No. 137,364.

To all whom it may concern:

Be it known that I, WILLIAM A. SMITH, a citizen of the United States, residing at Denver, in the county of Denver and State 5 of Colorado, have invented certain new and useful Improvements in Rock-Drills, of which the following is a specification.

The present invention relates to rock drills, and one of the primary objects is to 10 provide means whereby the controlling motor is moved to its work prior to being thrown into operation, the actuation of the motor being automatically effected when the same has been thus moved and properly 15 positioned.

A further object is to improve certain structural features, as will be hereinafter more fully pointed out.

In the drawings:

20 Figure 1 is a view in elevation of the drill, Figs. 2, 3 and 4 are sectional views therethrough on a scale of sufficient size to illustrate the details,

25 Fig. 5 is a cross sectional view on the line 5-5 of Fig. 2,

Fig. 6 is a cross sectional view on the line 6-6 of Fig. 2,

Fig. 7 is a cross sectional view on the line 7-7 of Fig. 3,

30 Fig. 8 is a cross sectional view on the line 8-8 of Fig. 3,

Fig. 9 is a detail rear elevation of the head block, with the rearwardly extending tube in cross section and taken substantially on 35 the line 9-9 of Fig. 3,

Fig. 10 is a detail longitudinal sectional view at right angles to Fig. 3, and illustrating the manner of clamping the parts together by the side bolts of the motor,

40 Fig. 11 is a detail sectional view illustrating the means for securing the hammer piston against rotation,

Fig. 12 is a detail sectional view through a portion of the cylinder member and hammer piston illustrating the relation of the motive fluid supply ports.

Similar reference numerals designate corresponding parts in all the figures of the drawings.

50 In the embodiment illustrated, a motor 13

of the hammer type is employed, which is connected to extensible fluid-operated feeding means, designated generally 14.

The motor 13 comprises a cylinder member 15 having a reciprocating hammer piston 16 therein, this hammer piston operating against a tappet 17 mounted in the front head 18 of the cylinder member, and said front head is provided with a suitable chuck to receive a drill bit, a portion of which is 55 shown at 19. The drill bit is provided with the usual bore 20 through which cleansing fluid is delivered to the inner end of the drill hole.

The motive fluid supply passage for the 60 motor 13 is shown at 21, being formed longitudinally in one wall of the cylinder member 15, and having lateral branches 22 which open through ports 23 into opposite sides of the cylinder wall. These ports are in constant 65 communication with longitudinal channels 24 formed in the opposite sides of the hammer piston 16, and terminating short of the ends thereof, said channels having their ends alternately brought into communication 70 with pockets 25 formed in the cylinder walls in line with said channels. Exhaust ports 26 open through the cylinder walls and communicate with an exhaust passage 27 that is 75 open to the atmosphere. In order to secure 80 the hammer piston against rotation or oscillation, and thus maintain the channels 24 in proper relation to the ports 23 and pockets 25, the said hammer piston is provided with a longitudinal keyway 28 terminating short of one end of the piston 85 hammer and engaged by a feather or key 29 secured in the cylinder wall.

The rear end of the cylinder member is 90 closed by a head block 30 to which is coupled the fluid-operated feeding means 14. As shown, this feeding means includes an inner tubular piston member 31 and an outer cylinder member 32 slidably telescoped therewith. The member 31, has its inner 95 end slidably fitted within a collar portion 33 projecting rearwardly from the head block 30, said end having an outstanding flange 34 abutted against said collar portion. A sleeve 35 fits over the collar portion and 100

flange, and has an inturned shoulder portion 36 abutted against the flange. For the purpose of rotating the drill, a rotating motor is shown at 37, and its shaft 38 has a 5 worm drive engagement 39 with a worm gear 40 formed upon a sleeve 41 that surrounds the piston member 31. It is believed to be unnecessary to go into detail regarding the drill rotating motor, the same having 10 the general characteristics of the structure disclosed in Patent, No. 1,196,042, dated August 29, 1916. The sleeve 41 has a flanged end 42 abutted against the rear end 35 of the sleeve. The various parts are held 15 in assembled relation by side bolts 43 engaged with the front head 18 of the motor, and passing through the sleeve 35 and the flange 42 of the sleeve 41. The outer end of the piston member 31 terminates in a 20 piston head 44, the tubular portion of said piston member being spaced from the surrounding cylinder member 32, and the head 44 having passageways 45 which permit the passage of fluid past said head.

25 Motive fluid to operate the feeding means and the hammer is supplied from any suitable source, through a hose line 46 which is coupled to a head 47 formed upon the inner end of the cylinder member, said hose line having communication with a valve chamber 48 formed in a valve casing 49 that is located on one side of said head. From this valve chamber 48, a passageway 50 opens into the cylinder member 32, said 30 passageway being controlled by a tapered throttle valve 51 rotatably mounted in the chamber, and having an exposed operating handle 52. The said throttle valve has a bore 53 in constant communication with the 35 fluid supply hose 46, and has a lateral port 54 movable into and out of communication with the port 50. It will thus be seen that when the valve 51 is opened, motive fluid will pass into the cylinder 32, around the 40 piston member 31 and through the passageways 45, so as to operate against the rear end of the piston head 44. This will cause said piston member to move upwardly and carry the motor and drill bit with it. The 45 fluid will also find its way through the head 44, which as shown in Fig. 4, is hollow, and thus enter the interior of the piston member 31. The head block 30 is provided with a passageway 55 having an off-set portion having an internal flange 56 constituting a tubular valve seat, and a pocket 57 is aligned with said off-set portion. Arranged in this passageway and co-operating 50 with the valve seat 56 is a plunger valve 58 which slides into and out of the seat 56 and is yieldingly held in co-operation with said seat 56 by a coiled spring 59 bearing thereagainst. The movement of the plunger valve under the action of the spring 59 is 55 limited by a plug 60 threaded into the head

block, said plunger valve having a nose 61 that abuts against the inner end of the plug. This plug also affords means for permitting access to the valve and its removal and replacement as will be evident by reference 70 to Fig. 8.

The valve in question is arranged to resist the passage of fluid from the feeding means to the motor, which fluid, it will be observed, is directly against the end face of the valve, and the valve 59 is so proportioned that said valve will not open until a predetermined pressure of motive fluid is brought against it.

To describe the operation of the structure as thus far explained, it may be stated that the valve 58 is set to resist a substantial pressure, say up to forty pounds, which pressure is sufficient to actuate the extensible feeding means. Assuming that the pressure of the motive fluid in the hose line 46 is at eighty pounds, it will be evident that if the throttle valve is turned slowly to admit fluid to the feeding means, the first action will be to extend said feeding means 90 and thus carry the motor and drill bit to their work. Motive fluid is, however, cut off from the motor by the said automatic plunger valve 58. When the pressure in the fluid operated feeding means rises above 95 forty pounds, said pressure will overcome the resistance of the spring 59, and the valve will be slightly opened, thereby admitting motive fluid to the hammer piston, and causing its actuation. The force of the 100 blows of such hammer piston, however, depends on the amount of air admitted by the throttle valve 51 and the consequent action of the piston valve.

The outer end of the feed cylinder member 32 is provided with a head 62 having a spur 63 to engage a support or abutment, and also having a means for connecting thereto a liquid supply pipe 64. This pipe has communication with a passageway 65 formed in the head 62, and threaded into said passageway, is a plug 66 having a bore 67 communicating with the passageway. Connected to the plug 66 is a liquid conducting tube 68 that extends longitudinally 110 into the feeding means and is slidably telescoped with another tube 69 that enters the same. A suitable packing gland 70 prevents leakage past the joint between the two tubes. The outer end of the tube 69 has a flange 71 115 and is located in a socket 72 formed in a projection 73 that extends rearwardly from the head block 30. A forwardly-extending liquid conducting tube 74 has its rear end flanged, as shown at 75 and located in the 120 socket 72. This tube 74 passes through the motor piston and tappet 17 and delivers into the bore 20 of the drill bit 19. Interposed between the flanges 71 and 75 of the tubes 69 and 74, is a packing washer 76 having 125

a bore 77 that affords communication between the tubes. A securing plug 78 is threaded into the socket, said plug surrounding the tube 69 and bearing against the flange 71 thereof. This plug, as will be evident, holds the tubes in place and is itself held against disengagement by a locking pin 79. With this arrangement, it will be evident that a cleansing liquid can be passed through the feeding means and motor to the drill bit. This particular arrangement involves certain structural improvements on Patent, No. 1,203,284, dated October 21, 1916.

The piston head 44 is provided with a bore 80 through which the tube 68 passes, and in which the plug 66 enters when the feeding means is in contracted condition. This bore is provided with a recessed portion 81 that is detachably engaged by a spring ring 82 mounted on the plug and serving to hold the parts against accidental extension.

For the purpose of lubricating the apparatus, a portion of the head block 30 is chambered, as shown at 83 and is provided with a port 84 communicating with the interior of the piston member 31 and a port 85 in communication with the passageway 55. A removable plug 86 affords communication with the chamber 83 to supply lubricant thereto. With this arrangement, lubricant will flow slowly from the chamber into the passageway 55, and be distributed by the motive fluid throughout the operating mechanism.

From the foregoing, it is thought that the construction, operation and many advantages of the herein described invention will be apparent to those skilled in the art, without further description, and it will be understood that various changes in the size, shape, proportion and minor details of construction, may be resorted to without departing from the spirit or sacrificing any of the advantages of the invention.

Having thus fully described my invention, what I claim as new, and desire to secure by Letters Patent, is:—

1. In apparatus of the character set forth, the combination with a motor, of a rear head block therefor having a rearwardly extending collar, extensible feeding means for the motor, including a member fitting within the collar and having an outstanding stop flange arranged at the end thereof, a sleeve fitting over the collar and flange and having an inset shoulder overlying said flange, and means for securing the sleeve on the collar and thereby retaining said member in place.

2. In apparatus of the character set forth, the combination with a motor, of a rear head block therefor having a rearwardly extending collar, extensible feeding means for the motor, including a member fitting within the collar and having an outstanding stop

flange arranged at the end thereof, a sleeve fitting over the collar and flange and having an inset shoulder overlying said flange, and side bolts for the motor engaged with the sleeve to hold the same and thereby the member in place.

3. In apparatus of the character set forth, the combination with a motor, of a rear head block therefor having a rearwardly extending collar, extensible feeding means for the motor, including a member fitting within the collar and having an outstanding stop flange arranged at the end thereof, a sleeve fitting over the collar and flange and having an inset shoulder overlying said flange, a drill rotating motor including a sleeve abutted against the first sleeve, and side bolts for the motor engaged with the sleeves to hold the same and thereby the member in place.

4. In apparatus of the character set forth, the combination with a motor, of extensible feeding means therefor, a head block interposed between the two and having a socket, oppositely extending fluid tubes respectively projecting into the motor and feeding means, and having their ends located in the socket, and clamping means securing said ends in said socket.

5. In apparatus of the character set forth, the combination with a motor, of extensible feeding means therefor, a head block interposed between the two and having a socket, oppositely extending fluid conducting tubes respectively projecting into the motor and feeding means and having their flanged ends located in the socket, packing interposed between the flanges, and means for securing the ends in the socket.

6. In apparatus of the character set forth, the combination with a motor, of extensible feeding means therefor, a head block interposed between the two and having a socket, oppositely extending fluid conducting tubes respectively projecting into the motor and feeding means and having flanged ends located in the socket, a packing washer interposed between the flanges and having a bore to afford communication between the tubes, and a nut located in the socket and holding the tubes in place.

7. In apparatus of the character set forth, the combination with a motor, of extensible feeding means therefor comprising an inner piston member connected to the motor and an outer cylinder member slidably thereon and having an outer end for abutment against a support, said outer end having an inwardly extending stem element and the piston member having a tubular portion to surround and receive the stem element when the parts are in contracted relation, and interlocking means carried by said stem element and tubular portion to hold the parts in contracted relation.

8. In apparatus of the character set forth, the combination with a motor, of extensible feeding means therefor comprising telescoping members, one of which is attached to the motor, the other having an outer end for abutment against a support, a cleansing fluid tube extending longitudinally in the feeding means and connected to said abutment end, and means mounted on the tube and de-

tachably engaging the inner member for 10 holding the feeding means in contracted relation.

In testimony whereof, I affix my signature in the presence of two witnesses.

WILLIAM A. SMITH.
